UNITED STATES PATENT OFFICE.

ALEXANDER E. BLOCK, OF ST. LOUIS, MISSOURI.

SHOE.

Application filed April 20, 1923. Serial No. 633,519.

My invention relates to improvements in shoes, and has for its object to provide a heel-and-shank reinforce of novel construction, partially rigid and partially flexible 5 functioning to sustain the weight of the wearer and to sustain and distribute said weight equally upon the heel and sole of the shoe. By means of the construction illustrated and described it is sought to keep the 10 counter in proper alinement with the heel, and both counter and heel in proper alinement with the sole, and to so hold the foot of the wearer as to prevent it from disturbing the normal balance of the shoe and 15 causing a run-over condition of the shoe, with resultant foot trouble.

An object of my invention is to produce a shoe having a flat heel-receiving portion, the principle of my invention in this regard 20 being diametrically opposed to the universal practice of cupping (making more or less concave) the shoe beneath the wearer's heel, as described in my former Letters Patent, No. 1,243,692, of October 23, 1917. That 25 cupping, regardless of its degree, I have found in practice to be injurious to the wearer's foot, and to be the cause of various injuries, distortions, and displacements of the wearer's heel from normal position. 30 In the normal human foot the heel bone at its base is semiglobular, and rests in a bed of flesh of considerable thickness, being held in place by the various muscles and ligaments. The bottom of the fleshy part of the 35 heel, when not under pressure from the weight of the body, is also rounded to a greater or less degree, but flattens more or less completely when sustaining the weight of the body.

40 When the heel of the foot rests in the concave portion of the interior of a shoe of such construction under the weight of the body, the flesh is pressed upward from a point near the center of the heel to its outer border, 45 and is forced and held in a position higher than that which is normal, forcing an holding the flesh upward in an abnormal position in relation to the heel bone. The continued holding of the flesh and bone in 50 these relative positions forces the base of the heel bone to sink into the flesh, and lessens the cushion capacity which that flesh has in the proper and normal use of the foot, as where the bare foot is used in walking upon 55 a hard surface, or where a flexible foot covering, such as a moccasin is employed. It is

this distortion of the flesh from its proper supporting position of the heel bone that is responsible for many of the troubles to which the heel of the human foot is subject. 60

Drawings.

Fig. 1 is a longitudinal mid-sectional view of a shoe embodying my invention.

Fig. 2 is a plan view of the upper face of 65 the outer sole with the re-inforcing element in place thereon.

Fig. 3 is a transverse sectional view of said reinforcing element, taken on the line 3—3 of Fig. 2. 70

Fig. 4 is an enlarged vertical median longitudinal section of the heel portion of a shoe embodying my invention.

Fig. 5 is a transverse vertical sectional 75 view of the same.

Description.

The reinforcing element or plate A comprises an inflexible body section 5 contoured to conform to the shape of the heel under 80 weight on a flat surface and having an outer edge thickened by a depending marginal flange 6, or like reinforcing means, said body section 5 terminating in a forwardly projecting resilient or flexible tongue 7, contoured as shown in Fig. 2. 85

A depressed median corrugation 8 extends from a point beneath the heel of the wearer to a point slightly to the rear of the tongue 7. In Fig. 2 the plane of the front wall of 90 the heel B is indicated by the dotted line 9—9, and said Fig. 2 indicates that the corrugation 8 extends slightly farther forward of the line 9—9 than to the rear of said line. 95

The plate A also has teeth 10 stamped from its rear portion and depressed downwardly and clinched into the outsole 11; while at or near the base of the tongue 7 a perforation 12 receives the rivet 13 by which the plate A is secured to said outsole 11 at a 100 point beneath the longitudinal arch of the foot of the wearer.

The contour of the rear edge of the plate or reinforce A, as shown in Fig. 2, is such that it fits within the line of nails or pegs 105 which unite the heel B and the shoe. The nail shown at 14 in Fig. 1, passes outside and beyond the plate A.

In a shoe of my improved construction a flat bearing surface for the wearer's heel is 110 provided, as well as a balanced support for the inner and outer longitudinal arches of

- the foot adjacent to the heel; the support being of sufficient width and strength to carry the weight of a distorted or broken arch.
- 5 To illustrate how this flat bearing surface is provided, the details of construction are given in Figs. 4 and 5, wherein the body section 5 of the plate A is shown as lying centrally in a flat heel-supporting area, the 10 portion of that area surrounding said body section 5 being suitably built up, as—for example—by the in-drawn lower edges of the upper materials of the shoe, those upper materials consisting of the heel-lining 17, 15 the counter 18, and the outer leather 19.
- The heel supporting reinforce A, as shown, is located between and in contact with the inner sole 16 and the outer sole 11 and within the inner edge portions of the 20 upper materials which are located between the outer and inner soles. By means of this construction the heel portion of the inner sole has a substantially flat heel receiving surface because of the underlying flat surfaced reinforce and the portions of the upper materials which are between the outer and inner soles and outside of the reinforce. Obviously that flat receiving surface for the heel of the wearer may be built up upon and 25 around the heel portion of said reinforce by various means and of various materials without departing from my invention as defined by the appended claims.
- The described and illustrated shoe and 30 heel-and-shank reinforce may each be varied in form and construction without departure from my actual invention as defined in the appended claims.
- As an example of a variation, it is a practice in the manufacture of some styles of 35 shoes to omit the outer sole at the heel receiving portion of the shoe. In such a case the top part or heel seat 15 of the heel serves the function of the outer sole.
- 40 This invention produces a shoe with a rest for the heel and the arch of the foot that is as close to nature as can be had with relation to its particular height of heel. To accomplish this the invention not only insures 45 a flat heel receiving surface at that part of the heel seat which rests above the heel of the shoe but extends that flat surface over the breast into the shank and on a plane with the heel seat portion and from there a 50 curve extends downward toward the 55 arch.

Claims.

1. The improvement in shoes comprising a heel-and-shank reinforce having a heel portion comprising a flat bearing surface and a depending marginal edge, and a projection at its front portion extending into the shank. 60
2. The improvement in shoes comprising a heel-and-shank reinforce having a depending marginal flange and a median longitudinal projection and being interiorly spaced from the edge of the heel seat and within the attaching nails. 65
3. The improvement in shoes comprising a heel-and-shank reinforce having a depending marginal flange and a median longitudinal projection and being interiorly spaced from the edge of the heel seat and within the heel attaching nails, said reinforce having a relatively flexible forwardly projecting tongue. 70
4. A shoe having a substantially flat faced heel supporting reinforce located between the outer and inner soles and filling the space between the edges of the upper materials which extend between the two soles, thereby insuring a substantially flat surface to receive the heel of the wearer. 80
5. A shoe having a substantially flat faced reinforce between and in contact with its inner and outer soles and filling the space between the edges of the upper materials which extend between the two soles, said reinforce having a part extending into the shank of the shoe, whereby a substantially flat surface is insured to receive the heel and arch of the wearer. 85
6. A shoe having a substantially flat faced reinforce between and in contact with its inner and outer soles and interiorly spaced from the edge of the heel seat and within the heel attaching nails, said reinforce insuring a substantially flat surface to receive the heel of the wearer. 90
7. A shoe having a permanent substantially flat faced reinforce with a thickened portion resting substantially at or in the middle of the heel and filling the space between the upper materials, said reinforce insuring a substantially flat surface to receive the heel of the wearer. 105

In testimony whereof I have hereunto affixed my signature.

ALEXANDER E. BLOCK.
